DESIGN FOR A CHECK WRITING MACHINE CASING

Willis A. Kropp, River Forest, Ill., assignor to Victor Adding Machine Co., Chicago, Ill., a corporation of Illinois

Application February 15, 1943, Serial No. 109,544

Term of patent 7 years

To all whom it may concern:

Be it known that I, Willis A. Kropp, a citizen of the United States, residing at River Forest, in the county of Cook, and State of Illinois, have invented a new, original, and ornamental Design for a Check Writing Machine Casing, of which the following is a specification, reference being had to the accompanying drawing, forming a part thereof, and wherein:

I claim:

The ornamental design for a check writing machine casing, as shown.

WILLIS A. KROPP.
